FIG. 7. Wallace White
ATTORNEY

UNITED STATES PATENT OFFICE.

HAZEL M. TAYLOR, OF NEW YORK, N. Y.

NECK PIECE.

Application filed December 23, 1925. Serial No. 77,172.

To all whom it may concern:

Be it known that I, HAZEL M. TAYLOR, a citizen of the United States of America, residing at 88 Central Park west, city, 5 county, and State of New York, have invented new and useful Improvements in Neck Pieces, of which the following is a specification.

This invention relates to a new or improved neck-piece more particularly intended for ladies' wear.

The object of the present invention is to provide an article of the class referred to which will be ornamental and pleasing in appearance, simple in construction and inexpensive to manufacture.

With this and other objects in view the invention consists in the new or improved neck-piece and in the novel combination of 20 parts hereinafter described with reference to the accompanying drawing which illustrates the preferred embodiment thereof.

In the drawing:—

Figure 1 illustrates a neck-piece according to the present invention in use.

Fig. 2 is a perspective view of the neck-piece separately.

Fig. 3 is a plan view of a piece of material adapted to be used in making up an 30 article according to this invention.

Fig. 4 is a similar view to Fig. 3 showing the piece of material illustrated in the latter figure after certain operations have been performed thereon.

Fig. 5 is a cross section taken on the line 5—5 of Fig. 2.

Fig. 6 is a similar view to Fig. 5 taken on the line 6—6 of Fig. 4, and,

Fig. 7 is a cross-sectional view of a fastening device employed.

In carrying out the present invention two pieces of any suitable cloth 2 of the shape shown in plan view in Fig. 3 are placed together and bound along their edges 45 with binding 4, thus forming a closed bag-like structure. Towards one end, that is to say, at 6, this bag is cut transversely, thus forming it into two parts or portions 8 and 10. Or, as an alternative two separate bag-like structures may be provided, one longer than the other, thus dispensing with the cutting operation.

A length of material is then taken and there is formed therefrom a ring, circle or 55 sleeve 12. This sleeve may also be of a double thickness of cloth bound at its edges

by binding 14 the same as the body portion of the article above described. It is to be noted, however, that it is not essential that said body portion or the sleeve be of double thickness; a single thickness of cloth may be employed if desired, although the double thickness is preferable as it imparts a certain degree of rigidity to the article. The binding, particularly if of a contrasting color, enhances the beauty of the article and gives a finish thereto but this also is not an essential factor.

Now to the inside front surface of the transverse sleeve 12 is connected as by 70 stitching, the part 10 of the body portion of the article, whilst to the inside rear surface of said sleeve is connected, also as by stitching, the part 8 of said body, said part 8 having been previously provided with one 75 part of a two-part snap fastener 16 preferably disposed near the cut edge of said part and in a central position transversely.

Some distance from the other end of said part 8, preferably about where the transverse stitching 18 in Fig. 4 appears, there is connected, as by stitching, the other part 20 of said snap-fastener. It will be observed that the part 16 of said fastener is connected to one face of said part, that is to say, to the front face, whilst the other part 20 is connected to the opposite face, that is to say, to the rear face of said part 8.

The construction described will be clear 90 from Fig. 5 where the various parts of the article are shown as consisting of a single layer of cloth suitably bound.

In order to use the article it is placed about the neck of the wearer and the free end 22 pulled through the sleeve 12 behind the part 10 but in front of the other (cut) end of said part (see Fig. 2), the two parts of the snap fastener are engaged and the article will then be secured in place with the central portion of the band about the neck and the two more or less ornamental end portions 10 and 22 projecting in opposite directions from the transverse sleeve 12.

It will be obvious that a plurality of snap fastener parts 20 may be employed in different positions along the length of material 8, thus adapting the article to correctly fit the neck of any particular person.

In order to enhance the appearance of the article the various parts entering into its composition may be gathered, tucked or

folded as indicated generally by the shading more particularly in Figs. 2 and 4 of the drawing, and more particularly in Fig. 6 where the material forming the part 8 5 of the article is shown folded back upon itself.

What I claim and desire to secure by Letters Patent is:

1. As a new article of manufacture a neck 10 piece comprising a length of cloth, a sleeve transversely secured to said length at one end thereof, a shorter length of cloth secured at one end to said sleeve in front of said first-mentioned length, and a fastening device 15 adapted to be hidden within the sleeve to secure the article about the neck of the wearer with the second mentioned length of cloth projecting outward from one edge of the sleeve and the free end of said first 20 mentioned length projecting outward on the opposite side of said sleeve.

2. A new article of manufacture comprising two bag-like structures of cloth, one of said structures being greater in length than 25 the other, a transverse sleeve or ring of cloth to which said structures are connected, and a multiple part fastening device adapted to be hidden within the sleeve for securing the article in place.

3. As a new article of manufacture, a neck 30 piece comprising a sleeve, a length of cloth secured at one end to the front part of said sleeve, a second length of cloth secured at one end to the rear part of said sleeve, the 35 free end of said second length of cloth being adapted to be passed through said sleeve in front of its connected end but behind the first mentioned length, and means carried by said second-mentioned length and hidden 40 within the sleeve for securing the article in place about the neck of the wearer.

4. As a new article of manufacture a neck piece comprising a sleeve, a short length of cloth secured to said sleeve and projecting laterally therefrom, a second and longer 45 length of cloth also secured to said sleeve behind said first mentioned length and projecting laterally from the opposite side of said sleeve and a two-part fastening device hidden in the sleeve for securing the article 50 about the neck of the wearer.

5. As a new article of manufacture a neck piece comprising a sleeve, a short length of cloth secured to said sleeve and projecting laterally therefrom, a second and longer 55 length of cloth also secured to said sleeve behind said first mentioned length, and projecting laterally from the opposite side of said sleeve and a multiple-part fastening device hidden in the sleeve for securing the 60 article about the neck of the wearer, one of said parts being secured to the front face of that end of the longer length of cloth which is secured within the sleeve and the co-operating part being secured to the rear 65 face of said length towards the opposite or free end thereof.

6. As a new article of manufacture, a neck 70 piece comprising a sleeve, a length of cloth secured at one end to the front part of said sleeve, a second length of cloth secured at one end to the rear part of said sleeve, the free end of said second length of cloth being adapted to be passed through said sleeve 75 in front of its connected end but behind the first mentioned length, and means carried by said second-mentioned length and hidden within the sleeve for securing the article in place about the neck of the wearer.

In testimony whereof I have signed my 80 name to this specification.

HAZEL M. TAYLOR.
